(57) **CLAIM**

The ornamental design for a package for wire and cable, as shown and described.

DESCRIPTION

FIG. 1 is an isometric view of a package for wire and cable according to our design;

FIG. 2 is a front view thereof;

FIG. 3 is a rear view thereof;

FIGS. 4 and 5 are side views thereof;

FIG. 6 is a top view thereof; and,

FIG. 7 is a bottom view thereof.

The broken lines in the drawing depict environmental subject matter only and form no part of the claimed design.
